US0D1099164S

(12) **United States Design Patent** (10) Patent No.: **US D1,099,164 S**
(45) Date of Patent: ** Oct. 21, 2025

(54) **DIVERTER BLOCK**

(71) Applicant: **PRL PERFORMANCE, LLC**, Salt Lake City, UT (US)

(72) Inventor: **Jason R. Greenawalt**, Greensburg, PA (US)

(73) Assignee: **PRL Performance, LLC**, Salt Lake City, UT (US)

(**) Term: **15 Years**

(21) Appl. No.: **29/846,690**

(22) Filed: **Jul. 19, 2022**

(51) LOC (15) Cl. **15-01**

(52) U.S. Cl.

USPC **D15/5**; D23/233

(58) **Field of Classification Search**

USPC D15/5; D23/233, 238, 257, 263

CPC F02M 37/0017; F02M 37/0047; F16K 17/00; Y10T 225/336

See application file for complete search history.

(57) **CLAIM**

The ornamental design for a diverter block as shown and described.

DESCRIPTION

FIG. 1 is a perspective view of the diverter block.

FIG. 2 is a front view of the diverter block.

FIG. 3 is a rear view of the diverter block.

FIG. 4 is a left side view of the diverter block.

FIG. 5 is a right side view of the diverter block.

FIG. 6 is a top view of the diverter block.

FIG. 7 is a bottom view of the diverter block.

FIG. 8 is an isometric view of the diverter block.

FIG. 9 is a front exploded view of the diverter block.

FIG. 10 is an isometric exploded view of the diverter block.

FIG. 11 is a right-side elevation view of the left-hand component of the diverter block with the right-hand component removed for ease of illustration.

FIG. 12 is a front elevation view of the left-hand component of the diverter block with the right-hand component removed for ease of illustration.

FIG. 13 is a left-side elevation view of the right-hand component of the diverter block with the left-hand component removed for ease of illustration; and,

FIG. 14 is a front elevation view of the right-hand component of the diverter block with the left-hand component removed for ease of illustration.

The broken lines are included for illustrating portions of the diverter block and form no part of the claimed design.

1 Claim, 12 Drawing Sheets
